UNITED STATES PATENT OFFICE.

MILTON C. BARBOUR, OF HERMOSA BEACH, CALIFORNIA.

GARMENT-RACK CARD HOLDER.

Application filed February 28, 1927. Serial No. 171,509.

My invention relates more particularly to a simple and practical device or marker which can be placed on a rod or bar adapted to receive garment hangers, said device or 5 marker being placed between groups of such hangers for indicating sizes, or grades, or other differentiations between the articles on opposite sides of the marker or card holder.

Among the salient objects of my invention 10 are to provide a device of the character referred to which can be placed upon a rod, pipe or bar at any place therealong and which cannot be accidentally removed therefrom; to provide a device which will hang 15 by gravity in an upright position so that a card or other data-bearing surface or face can be read conveniently; to provide a device which can be moved along on the rod or bar with the hangers as they are moved, 20 said device having means to prevent the hangers from being moved across the top of said device; to provide such a device with means forming a part thereof to prevent it from being lifted off of said bar or rod without 25 special manipulation; and, in general, to provide a simple, sheet metal division marker for use on the support for hangers which hold articles of various kinds, sizes and grades.

30 In order to fully explain my invention, I have illustrated one practical embodiment thereof on the accompanying sheet of drawings, which I will now describe.

Figure 1 is a top plan view of a device 35 embodying my invention;

Figure 2 is a side view thereof;

Figure 3 is an edge view thereof, with one side in section, and also showing a support with said device in place thereupon; 40 and

Figure 4 is a perspective view of a rack, with garment hangers thereon, and with my invention shown in place thereon.

Referring now more in detail to the drawings, my device as here illustrated is stamped 45 from sheet metal and comprises an arched body, 5, having its two ends, 6, 6, bent inwardly and upwardly, substantially as shown, to prevent accidental removal of 50 the device from the rod or support, 7. The opposite sides of each face of the device are turned over toward each other, as at 8, 8, to form a card receiving pocket to hold a card or ticket, 9, on which may be indicated

the particular information desired about the 55 garments or articles at either side of said device. The top of the device has a lip, 10, struck upwardly therefrom with which the device can be conveniently grasped in the hand, and it also serves as a means to prevent 60 the garment hangers, designated, 11, from being moved over the top of the same. When the hangers are moved along on the rod they engage with the lip, 10, and move 65 the marker along the rod therewith.

The device is readily applied to a rod, 70 pipe or other support by being pressed down over the same, the spring ends, 6, 6, yielding sufficiently to permit the device to pass over the rod or other support. Said ends, of course, prevent the device from being lifted 75 from the rod without being specially sprung outwardly for that purpose. The device has two pockets, one at each side, as indicated for cards or tickets, 9, 9.

The device is simple, cheap to manufacture, practical, and because the bulk of the weight is below the rod or support, said device will always hang in proper position and will always automatically return to its normal upright position.

I do not limit the invention to the details shown for illustrative and descriptive purposes, except as I may be limited by the hereto appended claims.

I claim:

1. A device of the character referred to comprising a sheet metal device of inverted U-shape adapted to straddle over a bar, the end being bent inwardly to underlie the bar 90 to prevent accidental removal, the outer face being formed into a pocket to receive a card, and the top being provided with an upwardly projecting lip, said device being adapted to hang and swing loosely upon a 95 bar in an upright position.

2. A sheet metal marker for bars comprising a U-shaped device having its ends bent inwardly and upwardly and adapted to spring apart to pass over said bar, pockets 100 on its opposite faces for cards, and an upwardly projecting lip, substantially as shown and described.

Signed at Los Angeles, Los Angeles County, California, this 18th day of February, 1927.

MILTON C. BARBOUR.
